(57) **CLAIM**

The ornamental design for a microengineered tissue barrier device, as shown and described.

DESCRIPTION

FIG. 1 is a front perspective view of a microengineered tissue barrier device showing our design.

FIG. 2 is a front view of the microengineered tissue barrier device shown in FIG. 1.

FIG. 3 is a rear view of the microengineered tissue barrier device shown in FIG. 1.

FIG. 4 is a left view of the microengineered tissue barrier device shown in FIG. 1.

FIG. 5 is a right view of the microengineered tissue barrier device shown in FIG. 1.

FIG. 6 is a top plan view of the microengineered tissue barrier device shown in FIG. 1.

FIG. 7 is a bottom plan view of the microengineered tissue barrier device shown in FIG. 1.

FIG. 8 is a bottom perspective view of the microengineered tissue barrier device shown in FIG. 1; and,

FIG. 9 is a perspective view of the microengineered tissue barrier device shown in FIG. 1, with the insert positioned within a cavity of the base shown in exploded-phantom view.

(Continued)

The broken lines, the areas within them, and the areas bounded by broken lines and solid lines depict portions of the microengineered tissue barrier device that form no part of the claimed design.
